UNITED STATES PATENT OFFICE.

CLYDE N. HATHAWAY, OF DETROIT, MICHIGAN.

CURTAIN-ROD-THREADING DEVICE.

Application filed April 15, 1926. Serial No. 102,129.

It is the primary object of my invention to provide a device adapted to be placed on the end of conventional domestic curtain rods to permit threading of the rods through the loop in the top of a conventional cloth curtain, to thereby prevent cutting or tearing of the curtain by the sharp edges of the rod.

With the above and other objects in view, my invention consists in the arrangement, combination and construction of the various parts of my improved device as described in the specification, claimed in my claims and shown in the accompanying drawing, in which:

Fig. 1 is an elevation of a curtain rod and curtain with my improved device applied to the end of the curtain rod.

Fig. 2 is a top or plan view of the same, with the curtain broken away.

Fig. 3 is a sectional view taken on line 3-3 of Fig. 2.

Fig. 4 is an elevation of a curtain rod, curtain and curtain rod attachment, certain parts being broken away showing a modification of my improved device.

Fig. 5 is a sectional view taken on line 5-5 of Fig. 4.

I have shown a conventional curtain rod 5, the constructions in Figs. 1, 2 and 3 being of the conventional "flat type" and the construction of Figs. 4 and 5 being of the conventional "round type". I have also shown a conventional cloth curtain 6 having a conventional loop 7 therein for the reception of the rod 5. In order to assist in running the rod 5 through the loop 7, I provide my improved device which is adapted to be mounted on the end of the rod and which in the forms shown in Figs. 1, 2 and 3, consists of a pair of U shaped channels 7 and 8 separated by the space 9 and converging to a rounded

nose 10. The end 11 of the device is slid over the end of the curtain rod 5, with the channels 7 and 8 engaging the bottom and top 45 of the rod, and the space 9 permitting of adjustment to meet varying sized rods. The tapered nose 10 and tapered portion 12 present a curved or smooth surface to the curtain 6 and prevent the sharp edges of the 50 curtain rod catching in the fabric of the curtain and tearing it.

In the construction shown in Figs. 4 and 5, the channels 7 and 8 form parts of circles, so as to engage the rounded form of rod 5. 55 The same general form of nose 10 is presented, as well as the same general form of space 9 between the channels and curved surface 12 joining the nose 10 and channels 7 and 8.

It will be obvious that various changes may be made in the arrangement, combination and construction of the various parts of my improved device without departing from the spirit of my invention, and it is my intention to cover by my claims such changes as may be reasonably included within the scope thereof.

What I claim is:

1. A curtain rod attachment comprising 70 a member formed with top and bottom channels, spaced apart and facing each other, said channels being joined at one end to form a curved end for said member, said channels being movable toward and away 75 from each other from the point of said end joinder.

2. A curtain rod attachment comprising 80 a member formed with top and bottom channels spaced apart and facing each other, said channels being joined at one end to form a curved end for said member.

CLYDE N. HATHAWAY.
